UNITED STATES PATENT OFFICE

ALBERTO ALBERT, OF BARCELONA, SPAIN

THERMOSTATIC CIRCUIT MAKING AND BREAKING DEVICE

Application filed April 30, 1927, Serial No. 188,021, and in Spain May 15, 1926.

The subject of this invention is an automatically operating device for giving a warning of sudden changes of temperature and also for giving a warning when the temperature has slowly varied and reached a previously determined temperature.

In the first case the device according to the invention is adapted for use for cases of fire and in the second for preventing accidents which might occur when the temperature of a certain place exceeds a given number of degrees.

One of the advantages of this apparatus resides in its mode of operation which permits a construction to be adopted which is strong and rigid and not liable to be damaged.

The device according to the invention is also characterized by its sensitiveness which makes it enter into operation when needed with great rapidity without, on the other hand, causing the optical or acoustic alarm signal, which forms a part of it, to enter into action unnecessarily.

The operation of this warning device is based upon the increase in length by expansion which metal rods undergo when subjected to heat and the greater or smaller degree of rapidity with which such increase takes place according to the cross sectional area of the rods.

A form of the device according to the invention is described hereinafter and illustrated in the accompanying drawing in which:

Figure 1 is a front view of the same and Figure 2 is a side view of Figure 1.

The apparatus essentially comprises a plate 1 of any material which is a poor conductor of heat and electricity. This plate has formed at its ends lugs or projections 2 and 3 in which are mounted three rods 4, 5 and 6 which are parallel with each other and run in the direction of length of the plate 1. These rods are secured at the lower part in the projection piece 3.

The central rod 5, of larger diameter than the outer rods, carries at its upper part a support 6' for the pivot 7 of a lever 8 and 9 having arms of unequal length. The end of the shorter arm 9 of this lever is pivotally

connected to the upper end of the rod 4 while the end of the other arm is adapted to make contact with the point 10 in which the rod 6 terminates. The rods 4 and 5 are connected together electrically and the first of them is provided with a terminal 11 to which is connected one of the wires 12 of the electrical installation in which the apparatus and the acoustic or luminous signal are connected.

The other wire is attached to the terminal 13 which is connected electrically with the rod 6 which is connected with the support 14 carrying a screw 15 which is adapted to establish contact, in the manner hereinafter described, with a lever or projection 16 secured to the support 6'.

Moreover, the end of the rod 6 is screw-threaded over a certain length and terminates in a knob 17. The screwthreaded portion of this rod engages in a corresponding thread in the projection 3 so that by turning the knob the distance separating the point 10 from the lever 8 can be varied.

At the same time the central rod 5 is covered with wire coiled around it, so as to increase the cross section of the said rod.

The operation of this apparatus is as follows:

Assuming that, in accordance with instructions which are necessary for the mounting and setting to work of the device, the latter is set to bring into operation the corresponding alarm signal in the case when the air which surrounds the device undergoes an unforeseen increase in temperature, for example an increase of 5° or else slowly increases in temperature to exceed 70°. If the air surrounding the apparatus slowly increases in temperature the rods 4 and 6 expand and consequently increase in length; but as under these conditions the central rod 5 also expands in this way contact between the lever 8 and the point 10 cannot be established and if under these conditions the temperature continues to increase, but slowly as stated above, there comes a moment when it exceeds the said 70° and the increase in length of all the rods becomes such that the part or projection 16 of the support 6' makes

contact with the screw 15 and thus produces the operation of the alarm signal.

If on the other hand the increase in temperature is sudden the increase in length of the rods 4 and 6 is rapid on account of their small cross section, so that under these new conditions as the central rod 5 does not increase in length so rapidly, the lever 8 is caused to be swung by relative movement between the rods 4 and 5, and makes contact with the point 10 to close the circuit of the said alarm signal.

The constructional details of the apparatus described may be varied as regard dimensions and the shapes of the parts and the materials of which the latter are made, the method of covering or protecting the same which is adopted, and the means for suspending or securing it may also be varied and in general all modifications may be made which do not alter, change or modify the essential nature of the invention.

What I claim is:—

1. A thermostatic circuit making and breaking device comprising a mounting which is a non-conductor of heat and electricity, a central rod on said mounting and two other rods, one on either side of said central rod, of smaller diameter than the central rod, the lower end of each of said rods being secured to the mounting, a support at the upper end of the central rod, a lever pivotally mounted at an intermediate point along its length on said support, the end of one arm of said lever being pivotally connected to the upper or free end of one of the outer rods, a point on the upper or free end of the second outer rod, which is adapted to make electric contact with the free end of the lever to close an electric circuit when a sudden rise in temperature takes place, a second contact connected with the second outer rod and adapted to make electric contact with the lever support to close the electric circuit in the event of a gradual rise to a dangerous temperature.

2. A thermostatic circuit making and breaking device according to claim 1, in which the two contacts are each adjustable in position.

3. A thermostatic circuit making and breaking device according to claim 1, in which the central rod is completely surrounded by a covering of wire so as to increase the cross-section of said rod.

In testimony whereof I have signed my name to this specification.

ALBERTO ALBERT.
